FIG.1.

FIG.2.

FIG.3.

FIG.4.

FIG.5.

FIG.6.

FIG. 1 is a front view of the kitchen hood embodying our new design with the face guard lowered;

FIG. 2 is a view similar to FIG. 1 showing the kitchen hood with the face guard elevated;

FIG. 3 is a rear view of the kitchen hood shown in FIG. 1;

FIG. 4 is a plan view of the kitchen hood as shown in FIG. 1;

FIG. 5 is a left-hand side elevation of the kitchen hood as shown in FIG. 1;

FIG. 6 is a left-hand side elevation of the kitchen hood as shown in FIG. 2.

The right-hand elevation is complementary to the left-hand elevation.

We claim:

The ornamental design for a kitchen hood, substantially as shown and described.
